Kiddle and Mansesson

ATTORNEYS.

UNITED STATES PATENT OFFICE.

OSCAR H. JOHNSON, OF DENVER, COLORADO, ASSIGNOR TO THE MINE AND SMELTER SUPPLY COMPANY, OF DENVER, COLORADO, A CORPORATION OF COLORADO.

MILL.

Application filed July 7, 1925. Serial No. 41,912.

This invention relates to an improvement in rod mills, that is to say, to an improvement in mills for reducing ores, cement, and the like, employing a rotary elongated or 5 cylindrical drum or shell containing loose, freely movable elongated reducing bodies or rods.

Among the objects of my invention is the provision of a mill of the type just referred 10 to, in which I employ an improved guard plate at the discharge end of the mill, this plate being of such a construction and so arranged that repairs, renewals, etc. may be easily effected.

15 In the drawings accompanying this application I have shown two embodiments of my invention;

Fig. 1 being a part sectional elevational view of one form of my invention;

20 Fig. 2 being an end view, partly in section, of the discharge end of the mill of Fig. 1; while

Fig. 3 is a fragmentary sectional elevational view of a modified form of mill.

25 Referring to the drawings in detail, 1 designates a rotary elongated cylindrical shell, drum or barrel provided with sectional wall liners 2 constituting or providing the reducing compartment 3 of the mill. This drum 30 is mounted at the feed end in a feed trunnion bearing 4, while adjacent the other end I provide the mill drum with a tire 5 resting upon rollers 6.

7 designates a feed hopper and 8 a screw 35 or screw conveyor by which material fed into the hopper 7 is carried forward into the reducing compartment 3 of the mill through the feed trunnion 4. The periphery of the drum and the feed head 9 of the mill are 40 provided with manholes 10 and 11, respectively, affording access to the interior of the drum for effecting repairs, renewals, or for any other purpose, it being understood that the mill may be re-rodded, re-lined, or any 45 other repairs or renewals made thereto through these manholes.

The discharge end of the mill is provided 50 with a frusto conical bell 12 bolted or otherwise secured to the body of the shell. Bolted to this bell and lying within the plane thereof is a discharge plate 13, provided with a central frusto-conical discharge opening 14. Across this opening I provide a bar or web 15, to which is bolted a frusto-conical plug 55 or filler 16 the base of which faces the inter-

rior of the mill. Within the bell 12 aforesaid and slightly spaced from the wall liners 2 I provide a sectional imperforate guard plate 17, this plate being assembled about the plug or filler 16. The plug 16 is hexagonal or noncircular in plan and beveled the inner edges 18 of the several sections 19 of the guard plate being correspondingly beveled or inclined, so that the several sections of the guard plate which are bolted to 60 the discharge plate 13 will prevent turning of the plug, the bolt 20 in turn preventing rearward movement of the plug, while the plug itself provides a partial support for and assists in maintaining the sections of 70 the guard plate in place. Between the front face of the guard plate and the inner face of the discharge plate 13, I provide lifters 21 secured in place by the same bolts which hold the guard plate in position. 75

The rear face of the guard plate 17, that is to say, the side facing or adjacent the crushing compartment 3 of the mill, is concave, as indicated at 22, the periphery of this concave portion of the plate extending 80 beyond the inner edge or face 23 of the wall liners 2. This prevents the rods from striking the edge of the guard plate when the mill is in operation and also prevents the rods from becoming caught between the 85 guard plate and the ends of the liners.

In the operation of the mill, the material which has been reduced by the rods in the reducing compartment 3 passes through the space left between the edge of the guard 90 plate 17 and the inner face of the bell 12, by reason of the guard plate which extends transversely of the mill being of smaller diameter than the mill, flows into the lifter compartment, where it is raised by the lifters 95 21 and finally is discharged through the discharge opening 14 in the discharge plate.

In making repairs or effecting renewals to the interior of the mill, access may be had to the reducing compartment through the 100 manhole 10, for example, and inasmuch as the guard plate 17 and the wall liners 3 are made in sections, these parts may be taken out through the manhole and repaired or replaced with new parts, as desired. The 105 mill may be re-rodded through the manholes 10 and 11 and bent or worn out rods may be removed and replaced through these same openings.

In the form of my invention illustrated in 110

Fig. 3 I have provided a structure somewhat similar to that shown in Figs. 1 and 2 and just described, the mill of this embodiment of my invention, however, having a trunnion discharge. In other words, this mill is supported at its discharge end on a trunnion instead of upon rollers, such as those indicated in Fig. 1.

Referring to this embodiment of my invention, 24 indicates the shell of the mill, which it will be understood is similar to the shell of the mill of Fig. 1, this shell being lined with wall liners 25. The feed end of this mill has not been illustrated, but it is to be understood that it is similar in all essential respects to the feed end of the mill of Fig. 1. The periphery of the mill drum is provided with a gear 26, by which the drum may be rotated. The forward or discharge end of this mill is frusto-conical, as indicated at 27, and is provided with a discharge bell or plate 28 bolted or otherwise secured to the frusto-conical end of the mill drum. To this bell 28 I bolt a guard plate 29. This guard plate is made in sections and is provided with a central cone, plug or filler 30, hexagonal, for instance, the setting up of the nuts on the bolts 31 by which the several sections of the guard plate are held in place also securely fixing this cone in position. The guard plate 29, which extends transversely of the mill, is of smaller diameter than the interior of the mill. The bell 28 is provided with lifters 32, by which the material as it discharges out of the reducing chamber 33 of the mill is lifted and allowed to flow out through the discharge trunnion 34, the cone 30 being concave, as indicated at 35, so as to provide a passageway 36 from the lifter compartment to the trunnion 34. The trunnion 34 may be made of any size desired and the cone 30 may be provided with a central opening 37, this opening affording means for renewing the grinding bodies in the drum of the mill, this opening being large enough to permit of the rods being passed through the same to the interior of the mill. The opening in the discharge plate or bell 28 and that in the trunnion 34 are in constant communication with each other. It is to be understood, of course, that the periphery of this mill will be provided with a manhole such as the manhole 8 of Fig. 1 for permitting a workman to enter the mill for the purposes of renewing the wall liners, renewing the sections of the guard plate 28, or for the purpose of making any other repairs or renewals that may be necessary or desirable.

The rear face of the guard plate 29 and of the plug 30 are concave, as indicated at 38, the edge of this concave portion, which I will designate 39, extending beyond the edge or face of the wall liners 25, so as to prevent injury to this edge by the reducing rods and

so as to prevent the reducing rods from becoming caught between the guard plate and the end of the mill or the end of the wall liners.

What I claim is:

1. A mill comprising a rotary drum, shell or barrel, a sectional imperforate guard plate adjacent the discharge end of the mill, and a central plug or filler member about which the sections of the sectional guard plate are assembled. 70

2. In a mill comprising a rotary drum providing a reducing compartment, loose, freely movable reducing bodies in said compartment, an imperforate sectional guard plate at the discharge end of said compartment, and a central plug or filler member providing a partial support for the sections of said sectional guard plate. 75 80

3. A mill comprising a rotary drum, shell or barrel, a sectional guard plate adjacent the discharge end of the mill and spaced from the walls thereof, and a central frusto-conical plug or filler member, the base of which faces the interior of said drum and about which the sections of said guard plate are assembled. 85 90

4. A mill comprising a rotary drum having a frusto-conical formation adjacent its discharge end, and a sectional guard plate lying within the plane of the said frusto-conical portion of the mill and having its periphery spaced therefrom to provide a discharge opening for the mill. 95

5. A mill comprising a rotary drum, sectional liners for the interior of the drum, a guard plate extending transversely of the mill and mounted adjacent the discharge end thereof and having its periphery spaced from the drum wall, the face of said plate adjacent the interior of the drum being of larger diameter than the interior of the drum. 100 105

6. A mill comprising a rotary drum, wall liners for said drum, a frusto-conical guard plate across the drum adjacent the discharge end thereof, the base of said cone facing toward the discharge end of the mill, the opposite face of said plate being concaved, the diameter of said concaved portion exceeding the inside diameter of the mill drum adjacent the inner face of the plate. 110 115

7. A mill comprising a rotary elongated drum or barrel, an imperforate guard plate adjacent the discharge end of the said drum, the inside diameter of the mill drum at the plate exceeding the diameter of the plate to provide a discharge slot between the drum and guard plate, a discharge plate at the end of the drum provided with a discharge opening, and lifters intermediate said guard plate and said discharge plate for effecting the transfer or flow of material, after it has passed the said discharge slot, through said discharge opening. 120 125 130

8. A mill comprising a rotary drum or shell, a discharge plate provided with a discharge opening attached to the discharge end of the drum, a sectional guard plate attached to said discharge plate, and a central plug or filler member about which the sections of said guard plate are assembled attached to said discharge plate.

9. In a mill, a rotary drum, a plate having a discharge opening therein attached to said drum and extending transversely thereof, a guard plate within the drum, and spaced from the walls thereof, to provide a discharge slot for the passage of material from the interior of the drum to said discharge opening, said plate being composed of sections or sectors disposed about a central plug or filler, and a member extending across said discharge opening to which said plug is attached.

10. In a mill, a rotary drum, a discharge head or plate attached to the discharge end

of the drum, and provided with a discharge opening, a discharge trunnion adjacent said head and constantly in communication with the opening in said head, a guard plate of smaller diameter than the interior of the rotary drum and extending transversely of the drum, said plate being made in sections, a central plug about which said sections are assembled, lifters between the guard plate and discharge head, said head, lifters and plate being attached to each other.

11. In a mill a rotary drum, a guard plate attached to the mill adjacent the discharge end thereof, said plate comprising a plurality of sections and a central plug or filler about which the several sections of the plate are assembled, said plug or filler being provided with an opening extending therethrough for the purpose set forth.

This specification signed this 25 day of June 1925.

OSCAR H. JOHNSON.
